US00D829903S

(12) **United States Design Patent** (10) **Patent No.:** **US D829,903 S**
(45) **Date of Patent:** **** Oct. 2, 2018**

(54) **SHIPPING WEDGE**

- (71) Applicant: **Covidien LP**, Mansfield, MA (US)
(72) Inventors: **Ernie Aranyi**, Easton, CT (US); **Tom Hessler**, Bethel, CT (US)
(73) Assignee: **Covidien LP**, Mansfield, MA (US)
(**) Term: **15 Years**
(21) Appl. No.: **29/550,821**
(22) Filed: **Jan. 7, 2016**

Related U.S. Application Data

- (63) Continuation of application No. 14/812,143, filed on Jul. 29, 2015.

(57) **CLAIM**

The ornamental design for a shipping wedge, as shown and described.

DESCRIPTION

FIG. 1 is a front, perspective view of a shipping wedge; FIG. 2 is a top view of the shipping wedge of FIG. 1; FIG. 3 is a right side view of the shipping wedge of FIG. 1; FIG. 4 is a left side view of the shipping wedge of FIG. 1; FIG. 5 is a bottom side view of the shipping wedge of FIG. 1;

FIG. 6 is a rear end view of the shipping wedge of FIG. 1; FIG. 7 is a front end view of the shipping wedge of FIG. 1; and, FIG. 8 is a back, perspective view of the shipping wedge of FIG. 1, attached to a staple cartridge.

The dashed broken lines are included for the purpose of illustrating environment and portions of the shipping wedge that form no part of the claimed design. The dot-dash broken lines define the bounds of the claimed design and form no part thereof.

1 Claim, 5 Drawing Sheets
